SYSTEM FOR THE TRANSMISSION OF SIGNALS TO RAILROAD VEHICLES

Lucien Joseph Armand Le Goff, Clichy, France,
assignor to Société d' Electricité Mors, Clichy,
France.

Application March 14, 1935, Serial No. 10,971
In France March 15, 1934

8 Claims. (Cl. 246—63)

For transmitting signals to railroad vehicles, it has already been proposed to use the induction between the rails and receiving devices carried by the engine: Usually, a current pulsated according to a given code is sent into the rails, each form of the code corresponding to a different indication. In known systems, the selection of the various indications is effected by means of electric devices which actuate relays, the attraction of 5 each of the relays varying according to the form of the code transmitted. These systems allow of producing under the eyes of the engine driver, through the medium of said relays, the lighting of certain lamps, in such a manner that the color 10 or arrangement of the lamps lighted allows the engine driver to be informed of the specific indications.

The present invention essentially differs, in its principle, from these systems. In fact, it particularly consists in the exact and detailed transmission, to the engine driver, of the code signs, either optically or by an acoustic means; a similar indication might moreover be obtained by using the sense of touch.

This arrangement has the following important advantages:

First.—It can be carried into practice without using any movable member on the vehicle, which is always liable to fail.

Second.—As it reproduces for the engine driver the detail of the codes, the slightest modification (intentional or not) of the code sent can be perceived by the engine driver.

Third.—It is easy to give to the code transmitted such a rhythm that it automatically incites the engine driver to effect the necessary operations; for instance, if three different indications are to be given to him, corresponding to the speeds permitted, he can be given an indication having a cantering rhythm for the highest speed, an indication having a trotting rhythm for an intermediate speed, and an indication of slow rhythm (walking) for lowest speed.

For giving indications to the engine driver, use 45 is made, on the engine, besides the windings directly influenced from a distance by induction, from the current circulating in the rails, of electronic valves, provided in suitable number, for allowing direct action on the optical, acoustic or like device perceptible to the engine driver.

The very principle of the invention leads to particular facilities. For instance, when the indication is given to the engine driver by means of a lamp which lights in front of his eyes at the 50 same pulsation as the code transmitted, nothing

is easier than to record these pulsations, for instance on a film (of the type used in kinematography) passing in front of the lamp at a predetermined speed. The recording is also effected without the use of any movable member on the 5 engine other than the film, this constituting a valuable advantage for an apparatus the operation of which must in no case whatever be unsatisfactory.

The detailed character of the indications given 10 to the engine driver must be emphasized, as it allows the latter to effect an intelligent selection at all times.

The system is applicable, with numerous modifications, as well to the apparatus located on the 15 track, as to the apparatus carried by the engine.

The following description, given by way of example, relates to a device in which the code emissions on the track are sent by means of a special pendulum and the reception is effected by means 20 of a luminescent tube exactly giving, without perceptible inertia, all the details of the code transmitted.

In the accompanying drawing:

Fig. 1 diagrammatically illustrates, by way of 25 example, the equipment of a track section supplied, according to the invention, with code current, with a single pendulum having multiple contacts when it is desired to transmit four indications to the vehicles moving on the track.

Fig. 2 is a diagrammatic view of the train or 30 engine equipment.

The track circuit A is fed, in the usual manner, by a source of current supply CA, with a protecting resistance DA, and allows the relay EA to be 35 energized to "line clear" position.

The signal transmission current, in the example under consideration, is an alternating current supplied by a generator G. This current is superimposed upon the normal track current by means 40 of a transformer FA.

The passage of the transmission current in the rails is regulated by a pendulum which, for that purpose, controls a number of contacts.

The pendulum is constituted by a magnetic body 1, supported by an arm 2, which is hung, by means of a joint, from a fixed point 3. The contacts controlled by the pendulum are of two types which will be hereinafter designated by the expressions "end position contacts" and "transitory contacts". In the example illustrated, the pendulum controls, concerning the transmission current, an "end position" contact and four "transitory" contacts.

The "end position" contact is substantially con- 55

stituted by a contact 4, carried by the arm 2 of the pendulum and electrically connected to one of the poles of the generator G. The end of the contact 4, through which current passes, comes, at the end of the right-hand stroke of the pendulum, in contact with the free end of a flexible member, such as a resilient blade 6, capable, under certain conditions, of being put in circuit with the other pole of the generator G.

10 A "transitory" contact also comprises a contact, such as 13^a, carried by the arm 2 of the pendulum and electrically connected to the pole of the generator G to which the contact 4 is connected. At a given point in the right-hand 15 stroke of the pendulum, the end of the contact 13^a comes in contact with the end of a flexible member 15^a, such as a resilient blade, the other fixed end of which is insulated. The conducting blade 15^a is, normally, in contact with a flexible 20 conducting member 18^a, normally connected, through the primary winding of the transformer FA, to the generator G. The flexible member 18^a is normally in contact with the blade 15^a, and the contact between these two members continues 25 during a definite movement of the pendulum towards the right.

The pendulum movement continuing, the member 18^a strikes against a stop 19^a which prevents it from following the subsequent movement of the 30 flexible blade 15^a under the action of the contact 13^a. During the further movement of the pendulum, the contact is therefore broken. When the pendulum returns towards the left, these phases take place in reverse direction.

35 The constitution and operation of the "transitory" contacts corresponding to the contacts 13^b, 13^c and 13^d are the same. These contacts are all connected to the same pole of the generator G; the flexible blades 18^b, 18^c are electrically connected, as well as the flexible blades 18^b, 18^d. They are electrically connected to a terminal of the primary winding of the transformer FA, with interposition of contacts hereinafter described, the other end of the primary winding 45 of the transformer FA being connected to the pole of the generator G opposed to that connected to the said contacts.

During a double oscillation of the pendulum from the vertical, by first starting towards the 50 right, the following electric paths are successively established, concerning the signaling current for the arrangement illustrated by way of example:

- (a) Path 13^a—15^a—18^a, then interruption of this path by the blade 18^a striking against the abutment 19^a;
- (b) Path 13^b—15^b—18^b, then interruption of this path by the blade 18^b striking against the abutment 19^b;
- 60 (c) Path 4—6; then breaking of the contact between 4 and 6;
- (d) Path 13^b—15^b—18^b then breaking of the contact between 13^b and 15^b;
- (e) Path 13^a—15^a—18^a, then breaking of the 65 contact between 13^a and 15^a;
- (f) Path 13^c—15^c—18^c, then interruption of this path by the blade 18^c striking against the abutment 19^c;
- (g) Path 13^d—15^d—18^d, then interruption of 70 this path by the blade 18^d striking against the abutment 19^d;
- (h) Path 13^d—15^d—18^d, then breaking of the contact between 13^d and 15^d;
- (i) Path 13^c—15^c—18^c, then breaking of the 75 contact between 13^c and 15^c.

The adjustment of the flexible members and of the abutments is such that the periods of time during which the various contacts are closed are exactly equal to the intervening periods of time during which said contacts are open.

5 The oscillations of the pendulum are sustained owing to the charging of the condenser C from the source of current supply S, through the limiting resistance R, by the blade contact 20, 23, 24 which is closed during a moment of the stroke towards the left, and to its discharge by the blade contact 8, 9, in the coil 12 which acts on the magnetic body 1.

10 The magnetic body 1, of inverted U-form, is suspended by its curvilinear portion from the arm 2. The coil 12 is disposed between the vertical branches whereby energizing of the coil will cause oscillation of the pendulum as above set forth.

15 The track section A, equipped as just stated, is continued, in the direction of the traffic, by sections B and C, the successive sections being insulated relatively to each other, as is well known.

20 Relays NB and NC characterize the condition of occupation of the sections B and C. When no axle is resting on the section B, the relay NB is energized; it is de-energized in the reverse case. When no axle is resting on the section C, the relay NC is energized, this closing the contacts KC allowing the energization of relay NC by the 25 source of current supply SC.

25 Under restrictive conditions of traffic ahead in the section A, that is to say when the section B is occupied, the relay NB is de-energized; this corresponds to the opening of a contact 30 and to 35 the closing of a contact 29 controlled by this relay the relay NC being energized under this "most restrictive" condition. The transmission current which reaches the rails of the section A is that which corresponds to the closing of contacts 4—6, in the circuit of which the contact 29 is 40 interposed. In these conditions, a short emission of the transmission current then occurs in the rails of section A.

35 In the case of medium restrictive conditions of traffic ahead in the section A, that is to say when the section B is unoccupied and the section C occupied, the relay NB is energized and the relay NC de-energized; the contact 30 is closed, the contacts 29 and 31 are open. The emission of 45 transmission current takes place through closing of the "transitory" contacts corresponding to the contacts 13^b and 13^d; there are four short emissions per double oscillation of the pendulum.

45 In the case of the least restrictive conditions of traffic ahead in section A, that is to say when the sections B and C are unoccupied, the relays NB and NC are energized: the contacts 30 and 31 are closed, the contact 29 is open. The emission of 50 transmission current takes place by the operation of four "transitory" contacts uniformly distributed on either side of the arm 2; there are two groups of four short emissions per double oscillation of the pendulum, the impulse in the code being made by the contacts 4—6.

55 The invention contemplates, by way of example, a particularly advantageous choice of types of code currents, but it is not limited to these types, the invention allowing a very great flexibility of 60 adaptation for the transmission of more or less than four indications (for instance the most restrictive indication is given by interruption of the transmission current).

65 Fig. 2 illustrates the equipment of a vehicle moving on the rails in the direction of the arrow f. 70 75

Windings X^1 , X^2 arranged on magnetic cores, are influenced by the variable transmission currents circulating in the rails. The currents received act on an amplifier Y . The current supplied by the amplifier actuates a receiver 62 .

According to the invention, the receiver R is a source of light conveniently constituted by a luminescent tube.

The modalities of illumination of the tube 62 are directly related to the variable transmission current and distinguish the signification without difficulty if the transmission codes have sufficiently characteristic rhythms, as is obtained in the case described by way of example concerning an installation for supplying a track with transmission current.

According to the invention, the control of the codes received is effected by inscription on a sensitive strip 68 . The tube 62 can be observed through a filter 64 ; it produces its actinic effect on the sensitive strip 68 through a filter 65 and an optical system 67 . Both filters 64 and 65 are opaque to external radiations liable to impress the film 68 .

A modification is also provided in which the emission of the transmission current is effected only when a vehicle occupies the track section under consideration, or the preceding track section. On the other hand, the current passing through the contacts of the pendulum or pendulums can, instead of having direct access to the rail, actuate a relay controlling the passage of the transmission current proper. This modification is particularly utilizable when the current circulating in the rails must be large.

As above stated, it is to be understood that the device might receive numerous modifications: Instead of luminescent tubes, use might for instance be made of a telephone receiver placed on the engine driver's ear, a vibrator placed under his fingers and the operation of which he can feel by the sense of touch.

The system above described, corresponds to a block device in which the code indications are selected by means of relays automatically operating through track circuits. It might be applied to any kind of signaling, the selection being produced by the position of the levers, signals, etc. On the other hand, instead of using, as above stated, a lamp having a bichromatic action, with selection, on the one hand, for the engine driver, on the other hand, for recording purposes, two distinct lamps might be employed, but, as previously stated, the description given has the advantage of avoiding any complication, which cannot be obtained with the arrangement comprising two different lamps.

It is to be understood that the necessary source of current supply on the engine might be of any type: storage batteries, turbo-generator utilizing the steam of the engine, etc. Instead of a luminescent tube, use might be made of filament lamps, but the latter, owing to their greater consumption, are more expensive.

What I claim as my invention and desire to secure by Letters Patent is:

1. In a system for indicating to the driver of a railroad vehicle at insulated sections the condition of traffic ahead, an equipment on the track for each section comprising a current generator connected to the rails by circuits, contacts in said circuits actuated by the oscillations of a pendulum, means for opening and closing certain of said circuits in relation to the condition of traffic ahead, a receiving device

on the vehicle influenced by the current circulating in the rails and the rhythmic indication of which is perceptible directly to the driver reproduces precisely the rhythm of said emission.

2. In a system for indicating to the driver of a railroad vehicle at insulated sections the condition of traffic ahead, an equipment on the track for each section comprising a current generator connected to the rails by circuits, contacts in said circuits actuated by the oscillations of a pendulum, contacts carried by the arm of said pendulum electrically connected to the generator and coming at the end of travel of the pendulum in contact with flexible conducting blades which close circuits connecting the generator to the rails, means for opening and closing certain of said circuits in relation to the condition of traffic ahead, a receiving device on the vehicle influenced by the current circulating in the rails and the rhythmic indication of which is perceptible directly to the driver reproduces precisely the rhythm of said emission.

3. In a system for indicating to the driver of a railroad vehicle at insulated sections the condition of traffic ahead, an equipment on the track for each section comprising a current generator connected to the rails by circuits, contacts in said circuits actuated by the oscillations of a pendulum, contacts carried by the arm of said pendulum and coming in contact during the travel of the pendulum each with an insulated flexible conducting blade normally in elastic contact with a second flexible blade connected to the generator, an abutment limiting the latter blade whereby beyond a certain amplitude the contact with the first blade is broken, means for opening and closing certain of the circuits in relation to the condition of traffic ahead, a receiving device on the vehicle influenced by the current circulating in the rails and the rhythmic indication of which is perceptible directly to the driver reproduces precisely the rhythm of said emission.

4. In a system for indicating to the driver of a railroad vehicle at insulated sections the condition of traffic ahead, an equipment on the track for each section comprising a current generator connected to the rails by circuits, contacts in said circuits, means for periodically actuating said contacts for controlling the opening and closing of said circuits in relation to the condition of traffic ahead, the rhythmic current thus emitted in the rails corresponding to said condition, and a receiving device on the vehicle influenced by the current circulating in the rails and the rhythmic indication of which is directly perceptible to the driver.

5. In a system for indicating to the driver of a railroad vehicle at insulated sections the condition of traffic ahead, an equipment on the track for each section comprising a current generator connected to the rails by circuits, contacts in said circuits, means for periodically actuating said contacts for controlling the opening and closing of said circuits in relation to the condition of traffic ahead, the rhythmic current thus emitted in the rails corresponding to said condition, a receiving device on the vehicle inductively influenced by the current circulating in the rails and comprising a luminous source visible to the driver illuminated during the passage of the induced current and extinguished during the non-passage of said current, thereby reproducing in a manner directly visible to the

driver the rhythm of the current emitted in the rails.

6. In a system for indicating to the driver of a railroad vehicle at insulated sections the condition of traffic ahead, an equipment on the track for each section comprising a current generator connected to the rails by circuits, contacts in said circuits, means for periodically actuating said contacts for controlling the opening 10 and closing of said circuits in relation to the condition of traffic ahead the rhythmic current thus emitted in the rails corresponding to said condition, a receiving device on the vehicle inductively influenced by the current circulating 15 in the rails and comprising a luminescent tube visible to the driver and illuminated during the passage of the induced current and extinguished during the non-passage of said current, thereby reproducing in a manner directly visible to the 20 driver the rhythm of the current emitted in the rails.

7. In a system for indicating to the driver of a railroad vehicle at insulated sections the condition of traffic ahead, an equipment on 25 the track for each section comprising a current generator connected to the rails by circuits, contacts in said circuits, means for periodically actuating said contacts for controlling the opening and closing of said circuits in relation to 30 the condition of traffic ahead the rhythmic current thus emitted in the rails corresponding to said condition, a receiving device on the vehicle inductively influenced by the current circulating in the rails and comprising a luminous source

visible to the driver illuminated during the passage of the induced current and extinguished during the non-passage of said current, thereby reproducing in a manner directly visible to the driver the rhythm of the current emitted in the rails, and a sensitive cinematographic registering strip in position to be impressed by said luminous source. 5

8. In a system for indicating to the driver of a railroad vehicle at insulated sections the condition of traffic ahead, an equipment on the track for each section comprising a current generator connected to the rails by circuits, contacts in said circuits, means for periodically actuating said contacts for controlling the opening 10 and closing of said circuits in relation to the condition of traffic ahead the rhythmic current thus emitted in the rails corresponding to said condition, a receiving device on the vehicle inductively influenced by the current circulating 15 in the rails and comprising a luminous source visible to the driver through a filter, said source being illuminated during the passage of the induced current and extinguished during the non-passage of said current in such manner as to 20 reproduce the rhythm of the current emitted in the rails, and a sensitive cinematographic registering strip in position to be impressed by said luminous source through a filter complementary 25 to the first filter, so that any light ray capable 30 of impressing said strip cannot escape the ensemble of the two filters. 30
